Primary Examiner — Mitchell I. Siegel(74) *Attorney, Agent, or Firm* — Mark D. Bowen, Esq.;
Malin Haley DiMaggio & Bowen, P.A.(57) **CLAIM**

The ornamental design for a golf training apparatus, as shown and described.

DESCRIPTION

FIG. 1 is a top perspective view of a golf training apparatus in accordance with the present invention;

FIG. 2 is a bottom perspective view thereof;

FIG. 3 is a top view thereof;

FIG. 4 is a bottom view thereof;

FIG. 5 is a left-side view thereof, with the right-side view being identical;

FIG. 6 is a front view thereof, with the rear view being identical; and,

FIG. 7 is a front view thereof illustrating the environment associated with the claimed design.

The broken lines in FIG. 7 illustrating a golfer are directed to environment for illustrative purposes only and form no part of the claimed design.

1 Claim, 6 Drawing Sheets(56)
